UNITED STATES PATENT OFFICE.

LOUIS W. MILLER, OF ROCHESTER, NEW YORK, ASSIGNOR TO NATIONAL POLICE SIGNAL COMPANY, OF BUFFALO, NEW YORK, A CORPORATION OF NEW YORK.

ELECTRICAL COMMUNICATING SYSTEM.

1,080,018.

Specification of Letters Patent.

Patented Dec. 2, 1913.

Application filed March 17, 1909. Serial No. 484,016. Renewed February 19, 1912. Serial No. 678,748.

To all whom it may concern:

Be it known that I, LOUIS W. MILLER, of Rochester, in the county of Monroe and State of New York, have invented certain new and useful Improvements in Electrical Communicating Systems; and I do hereby declare the following to be a full, clear, and exact description of the same, reference being had to the accompanying drawings, forming a part of this specification, and to the reference-numerals marked thereon.

The present invention relates to electrical communicating systems and it has for an object to provide a system over which either fire alarm reports or calls may be sent or telephonic communications may be maintained, preferably having provision for giving precedence to the fire alarm reports.

Another object of the invention is to provide a telephone system in which the time of the call from a substation is automatically recorded in order that the system may be employed for making records of the times of the reports of policemen, watchmen and others who are required to make periodical returns to central offices.

A still further object is to provide a fire alarm system in which the sender of the alarm or call may be signaled that the alarm has been received and in this way assured that the system is in working condition.

To these and other ends the invention consists in certain improvements and combinations of parts all as will be hereinafter more fully described, the novel features being pointed out in the claims at the end of the specification.

In the drawings: Figure 1 is a diagrammatic view of one line of a telephone system designed for recording the times of the reports of policemen or watchmen, there being combined therewith means adapting the line for the transmission of fire alarm signals; Fig. 2 is a diagrammatic view of the central office apparatus for connection to the line; Fig. 3 is a detail view of one of the time recording mechanisms, and Fig. 4 is a diagrammatic view of a line in the system designed for use in a factory or other large building or plant in which a watch-

man or watchmen travel from station to station and report at each station, the report being automatically recorded in the building and also at some central point, such as a telephone office or police station.

In the embodiment of the invention illustrated in Fig. 1 each line is preferably a normally closed circuit having a substation and a central station and comprising line conductors 1 and 2 and a suitable source of energy, such as central station battery 3; a high resistance comprising in this instance resistance coil 4 and the windings of a signal or electromagnetic bell 5, being preferably arranged in the circuit. Bridged across the circuit in order to short circuit the high resistance is a telephone instrument set comprising a transmitter 6 connected to the lines 1 and 2 by a conductor 7 having a primary coil 8 therein acting on the secondary coil 9 which is connected to the receiver 10, the receiver being preferably supported as is usual upon a hook 11 which controls switches 12 and cuts out the instrument set when the receiver is arranged

on the said hook. The branch in which the instrument set is positioned may also be provided with switches 13 which have a normal tendency to close and are controlled by the door 14 of the inclosure 15 that houses the instrument set and is preferably locked so as to be accessible only to authorized persons. It is apparent that when the door 14 is moved to closed position the switches 13 will be moved to break the shunt circuit 7 thus cutting out the instrument set. The advantage of this arrangement is that the signal 5 may be operated from the central station in a manner to be described, even though the receiver 10 has not been returned to its hook 11 through either design or carelessness. Arranged at the central station to be operated on the removal of the receiver 10 from its hook is the operator's signal or supervisory, which in this instance, embodies a conductor 16 leading from line wire 1 to the lamp 17 and a conductor 18 leading from the lamp and connecting with a movable switch member

19 that is adapted to cooperate with contact

20 connected by conductor 21 with the contact 22. The contact 22 is adapted to be engaged by the armature switch 23 which, by conductor 24, connects with line wire 2. 5 The operation of the armature switch 23 may be effected by one pole of the compound wound electro-magnet 25 whose windings are arranged in the main line. Although this magnet is arranged in a closed circuit, 10 it is not energized until the high resistance 4, 5 is short circuited, but when this latter action takes place it draws the armature switch 23 to the contact 22 thus effecting the illumination of the operator's supervisory lamp 17. Upon the illumination, the operator connects with the line, this connection preferably being effected by the jack contacts 26 and 27 which by conductors 28 and 29, respectively, connect with the line 15 conductors 1 and 2, a condenser 30 or other means being interposed between the jack and the line conductors to prevent the resistance 4, 5 being short circuited at the jack to effect the operating of the recording 20 mechanism which will be hereinafter described. When the central operator makes connection with the line the switch 19, which is connected by a member 31 with contact 26, is shifted away from the contact 20 thus 25 extinguishing the lamp 17 which remains in this condition until the instrument set at the substation is cut out, when the magnet 25 is deenergized and the armature switch 23 moves away from the contact 22. In 30 moving away from the contact 22 it cooperates with a contact 32 which, by a conductor 33, is connected to the contact 34 lying in proximity to the switch 19 and engaged by the latter when the central operator 35 makes a connection with the line, thus again illuminating the lamp and notifying the operator that the line is not in use. The central office apparatus preferably comprises a plug member 35 connected to a 40 listening key 36 by conductors 37, the listening key having the operator's transmitter and receiver connected therewith, there being also provided a plug 38 connected to the listening key for making connection 45 with another line. In order that the central operator may operate the signal 5 there is provided a ringing generator 39 adapted to be bridged across the circuit. For this purpose the conductors leading from the generator 39 connect with contacts 40 on the switch board and the line wires 1 and 2 lead to the switch board and are provided with switches 41 normally held in engagement with contacts 42 also arranged on the 50 switch board in proximity to the contacts 40. A push button 43 operates between the switches 41 to move them into engagement with the contacts 40, thus cutting out the battery and the operator's signal and the 55 recording mechanism at the central station.

Combined with the telephone system is a time recording mechanism which is so connected with the system that it is operable from the substation only. To this end an electromagnet 44 is arranged in the line so as to be disconnected from the substation by the switches 41. This magnet controls a time recording mechanism and is only energized whenever the receiver 10 is removed from the hook 11 to short circuit the high resistance 4, 5. Immediately after it operates the time recording mechanism, it is short circuited by a shunt circuit 45 embodying an armature switch 46 which is moved to close the circuit 45 by a pole of the double wound magnet 25 which also is only energized when the resistance 4, 5 is cut out. The time recording mechanism may be of any desired construction. In the present instance it embodies recorders 47 corresponding in number to the number of lines in the telephone system and each being preferably in the form of a punch operating upon a record member 48 which may be common to a number of recorders 50 and have divisions thereon corresponding to the number of lines leading to the time recording mechanism. The sheet is preferably driven by a clock mechanism 50 and has also divisions 49 thereon corresponding to the divisions of a clock, a perforation on the sheet indicating the time of the report and the substation from which the report is sent. To operate the punch 47 there may be employed a lever 50 pivoted immediately of its ends at 51 and having one arm cooperating with the punch and the other arm acting as an armature for the magnet 44. It will thus be seen that when the armature 44 is energized the lever 50 will be moved to operate the punch 47 and immediately thereafter the electromagnet 44 is deenergized, owing to the short circuiting thereof by the shunt 45. Also arranged at the substation in the main line is a make and break device 52 which is normally held in a position to maintain the circuit closed. In order to effect the opening of the circuit there may be pivoted in proximity to this make and break device a switch lever 53 or other device which cooperates with a portion 54 of the movable member of the make and break device and breaks the circuit for an instant, this being due to the end of the lever riding on oppositely inclined walls of the portion 54. When the lever 53 is moved to break the circuit, it moves into engagement with a contact 55 and throws in a shunt circuit 56 which short circuits the high resistance 4, 5 and also the telephone instrument set. The lever 53 is held in this position by an electromagnet 57 which becomes energized when the switch lever 53 is shifted to short circuit the high resistance. The lever 53 may be arranged 130

within the closure 15 at the substation, and the means for effecting its operation is preferably in the form of a push button 58 normally shielded by a fragile plate 59 on the exterior of the enclosure. The purpose of this make and break device is to enable a fire alarm signal or call to be sent over the telephone line, the break in the circuit actuating the signaling device at the central station. The present construction of this signaling device is in the form of a hinged member or flap 60 arranged on the switch board in proximity to the supervisory lamp 17 and normally held in an unsignaling position by a latch 61 which, in this instance, forms an arm on the armature 62 arranged in proximity to an electromagnet 63 the winding of which is in the main circuit and is energized at all times excepting when the main circuit is broken when it releases the signal 60. The pushing of the button 58 it will be remembered also short circuits the high resistance and consequently the lamp 17 is illuminated and this illumination together with the falling of the signal 60 indicates to the operator that a fire call has been sent in from the substation. The central operator thereupon pushes the button 43 which effects the breaking of the main circuit and consequently the deenergization of the magnet 57 and release of lever 53 which moves away from the magnet under the action of spring 153. This button also connects the ringing generator 39 with the line thus signifying the party sending in the alarm that the alarm has been noted. The release of the button restores the line to its normal condition. The dropping of the signal 60 without the illumination of the lamp 40 will indicate to the operator that the line is broken.

The embodiment illustrated in Fig. 4 is designed for factories or other large buildings or plants in which a watchman or watchmen are required to travel from point to point and to make a report at each point. The system makes an individual record for each substation at the factory or building showing that reports have been sent in from the different substations and also makes a record at the central station, this record, however, being common to all of the substations on one particular line. The central station is, in this instance, the same as that shown in Fig. 1, and the main circuit 1 and 2 has a high resistance the same as that shown in Fig. 1. Instead of one substation being connected to each line, a plurality of substations is employed, three in the present instance, adapted to be connected in multiple to the main line and each arranged to cut out the high resistance. The time recording mechanism at the building is the same as that shown in Fig. 1 and has a plurality of recorders 27 corresponding in number to the

number of substations on the circuit. The magnets 44 which control this auxiliary recording mechanism are arranged in multiple, being connected to the line conductors 1 and 2 by branch or shunt circuits 64 which are normally open but are each provided with a switch or make and break device 65 which, when closed, short circuits the resistance 4, 5 and operates the individual recorder on the auxiliary time recording mechanism and the common recorder on the main recorder mechanism at the central station. The switches 65 are located at the substations and each is preferably controlled by an instrument at the substation. To this end each receiver hook 11 is provided with a depending extension 66 which cooperates with a projection 67 on the switch 65 and moves the latter into engagement with contact 68, and immediately afterward releases said switch to permit it to move away from the contact. It is desirable to break the main circuit in order to cut out the telephone instrument set from the line so that sufficient energy may be obtained from the battery 3 in order to energize the magnets of the main and the auxiliary recording mechanisms. For this purpose there is provided in the main line at each substation a switch 69 which normally holds the line closed but which, when moved away from its contact 70, cuts out all of the telephone instruments. This switch 69 is preferably operated from the contact 68 immediately after the switch 65 has engaged contact 68, this being preferably accomplished by a mechanical connection 168. The engagement between contact 68 and the switch 65 is only for a moment for after the depending portion 66 of the receiver hook 11 has passed over the projection 67 the shunt circuit 64 is cut out and the main circuit again established. From this it will be seen that it is possible to send in a report from any one of the substations even though conversation is taking place on the line. A fire alarm report may also be sent in from any of the substations and this without regard as to whether the telephone instruments are being used. With this end in view the shunt circuits 56 are adapted to be connected in multiple to the main circuit by their controlling switches 53 which also actuate make and break devices 52 in the main line and are held in their shifted positions by electromagnets 57. The central operator answers the call in the same manner that the call is answered in the construction shown in Fig. 1.

Assuming that the invention is employed as a police telephone and fire alarm system, there will be a number of lines leading from different points along the beat of an officer to a central station, such as police headquarters or a precinct station. The officer travels from one telephone substation to an-

other and reports at each station. In reporting he removes the receiver 40 which closes switches 12 and cuts out the high resistance 4, 5 thus energizing electromagnets 25 and 5 41. The latter actuates the time recording mechanism making a punch mark in the individual record for the substation and is immediately short circuited by switch 46 so as not to retard the operation of the time driven 10 record. The magnet 25 effects the operation of switch 23 which causes the lamp 17 to be illuminated thus notifying the central operator who connects with the line and ascertains from the voice of the sender whether 15 the proper person is making the report. In connecting with the line the central operator automatically extinguishes the lamp 17 and if the officer desires to connect with another line the plug 38 is employed, the deenergization 20 of magnet 25 causing the lamp 17 to be again illuminated to notify the central operator that the conversation has ceased. If the officer fails to hang up the receiver when he closes the door 14 the telephone instrument 25 set will be cut out by the switches 13, thus permitting the substation to be called. The calling of the substation is effected by the generator which connects with the line after 30 the recording mechanism and the operator's supervisory has been cut from the line.

The fire alarm signal may be sent by any one upon breaking of the plate 59, and pushing of the button 58. This breaks the normally closed line circuit and deenergizes 35 the magnet 63 which releases the signal 60. The resistance 4, 5 is at the same time short circuited thus illuminating the lamp 17 and operating the recording mechanism. The central operator thereupon presses button 40 43 to release switch 53 and operate the signal 5 at the substation in order to notify the sender of the alarm that the call has been noted. The button 58 could be used for some other purpose than a fire alarm call as 45 it may be employed to permit private individuals to call the police.

When the system is arranged in a factory or other plant the operation at the central station is substantially the same. The removal of a receiver also operates a recording mechanism at the factory so that a complete record of the reports of a watchman or watchmen may be obtained at any time while there is at all times a supervision being maintained at the central station.

A system constructed in accordance with this invention will add materially to the efficiency of a police force of a large city as a complete record of each officer may be obtained with very little trouble, as each officer on the line has an individual record, or in other words, one which is separated from the others. Any number of reports may be sent in simultaneously without interference, 65 as each substation has a separate connection

with the recording mechanism. The approximate location of an officer at a particular time can be found out immediately and he may be called to headquarters merely by signaling the last substation at which he has reported or the one at which he is next to report. It is impossible for the officer to send in a report by another party as he must talk with the central operator who will be familiar with his voice. The central operator cannot interfere with his report favorably or otherwise as the recording mechanism is controllable only from the substation and the report is made whether the operator answers or not. The officer cannot offer as an excuse for his failure to report that the line was out of order when such is not the case for on the breaking of the line the central operator is signaled.

The fire alarm feature may take the place 85 of the usual fire alarm system or may be used in conjunction therewith when it will offer that much greater security against the spread of fires. Even should one of the lines get out of order the whole system is 90 not rendered inoperative as with the present fire alarm systems and the sender of the alarm is assured that the report has been received as he obtains a signal from the central office.

When the factory system is employed it is possible to maintain constant supervision of the watchmen for should they fail to report to the central operator immediately inquiry is instituted to ascertain the reason 100 therefor. While the central operator cannot know from which substation the report is sent in yet it can be ascertained by an inspection of the auxiliary recording mechanism whether the usual rounds have been 105 made.

While the initial cost of this system is not greater than those at present used, the cost of maintenance is less, and the greater efficiency secured both in police and in fire 110 protection soon pays for its installation.

I claim as my invention—

1. The combination with a telephone system embodying a substation and a central station, of an electrically-operated time-recording mechanism having connection with the system, and means preventing the control of the time recording mechanism under normal line conditions of service except from the substation.

2. The combination with a telephone system embodying a line having a substation and a central station, of a central office apparatus adapted for connection to the line at the central station, a time recording mechanism having connection with the system, and means preventing the control of the recording mechanism from the central office apparatus.

3. A telephone system comprising a line,

- an operator's signaling circuit controlled by the line, a jack connected to the line, a condenser between the jack and the line, substation instruments controlling the signaling circuit, a time recording mechanism, and an electromagnet controlling the time recording mechanism, and connected to the line independently of the signaling circuit and the jack. 65
10. 4. The combination with a source of energy, a line connected thereto having a central station and a substation, a switch at the substation to control the line, substation instruments connected to the line, a supervisory circuit controlled from the substation switch, a jack connected to the line, a condenser interposed between the jack and the line, and a central office apparatus for connection to the jack, of an electromagnet 70 arranged to be operated on the closing of the switch, and a time recording mechanism controlled by said electromagnet. 75
5. The combination with a normally closed line circuit, a time recording mechanism comprising an electromagnet arranged in said circuit and a resistance interposed in the line circuit normally rendering said magnet inoperative, of a normally open shunt circuit leading around the resistance, 80 means for closing the shunt to permit the energizing of said magnet, and further means for deenergizing the time recording magnet after its operation. 85
6. The combination with a line, of an electromagnet controlled from the line, a time recording mechanism controlled by the magnet, and means for short circuiting said magnet to effect its deenergization and render it inoperative immediately after the time recording mechanism has been operated. 90
7. The combination with a line, of an electromagnet having its windings connected to the line, a time recording mechanism operated by said magnet, and means for short circuiting said magnet after the latter has operated the recording mechanism. 95
8. The combination with a line, of an electromagnet having its windings connected to the line, a second magnet having its windings connected to the line, and a short circuit for the first mentioned magnet embodying a switch controlled by the second mentioned magnet. 100
55. 9. The combination with a normally closed circuit having a resistance therein, of means arranged to short circuit the resistance, and a time recording apparatus embodying a record sheet and mechanism operated automatically to record a permanent record on said sheet upon the short circuiting of the resistance by said means. 105
10. In a telephone system, the combination with a normally closed circuit having a 110
- substation and a central station, of a resistance in the circuit at the substation, substation telephone instruments arranged to short circuit the resistance, an electromagnet in the circuit, energized when the resistance is short circuited, and a time recording apparatus comprising a record number and mechanism for making a permanent record on said member controlled by said magnet. 115
11. In a telephone system, the combination with a normally closed circuit having a substation and a central station, of a resistance in the circuit at the substation, a substation telephone instrument set arranged to short circuit the resistance, an electromagnet in the circuit, a time recording mechanism controlled by said magnet, a second magnet in the circuit, and means operated by the second magnet for deenergizing the first named magnet immediately after the time recording mechanism is operated. 120
12. In a telephone system, the combination with a normally closed circuit having a substation and a central station, of a resistance in the circuit at the substation, a substation telephone instrument set arranged to short circuit the resistance, an electromagnet in the circuit, a time recording mechanism controlled by said magnet, a second magnet in the circuit, and a shunt circuit having a member moved by the second named magnet to short circuit the first named magnet. 125
13. The combination with a normally closed circuit having a resistance therein, of substation instruments arranged to short circuit the resistance, and an operator's signal and a recording mechanism both operated on the short circuiting of the resistance by the substation instruments, the former signaling the operator and the latter effecting a permanent record of the time said signal was despatched. 130
14. The combination with a line, having a central station and a substation, an electromagnetically controlled signal connected to said line at the central station, an instrument at the substation for controlling said signal, a signal at the substation, a time recording apparatus embodying a record member and mechanism at the central station controlled by the line for marking said record member, a signaling generator at the central station, and means for breaking the connection of the time recording mechanism with the line and for connecting the generator thereto. 135
15. The combination with a normally closed circuit having a central station and a substation, a substation controlled by the circuit, a resistance in the circuit and a source of energy at the central station, of a substation instrument arranged to short circuit the resistance and the signal, a recording apparatus embodying a record member. 140

- and mechanism adapted to be operated upon the short circuiting of the resistance by the substation instrument for making said record member, a signaling generator at the 5 central station, and means for connecting the generator to the closed circuit to operate the substation signal and to cut out the recording mechanism.
16. The combination with central and 10 substations, a normally closed circuit connecting them and two time recording mechanisms both embodying electromagnets, one of which is arranged in said circuit and a normally open circuit for the other electro- 15 magnet, of a resistance interposed in said circuit and normally rendering said magnet inoperative, a normally open circuit for the other magnet forming a shunt leading around said resistance and a switch for clos- 20 ing the shunt circuit to cut out the resistance and permit the energizing of both magnets.
17. The combination with a line circuit having a plurality of substations, of a time recording mechanism common to all of said 25 substations having a recording electromagnet adapted to be controlled by all of the substations, and a time recording mechanism having a plurality of operating electromagnets, each of which is adapted to be con- 30 trolled by a separate substation.
18. The combination with a plurality of substations, a normally closed circuit connecting them, a recording mechanism having an electromagnet arranged in said cir- 35 cuit and adapted to be controlled by all of said substations, and a resistance in said circuit normally rendering the magnet inoperative, of a separate recording mechanism having a plurality of electromagnets, one for 40 each substation, substation branch operating circuits leading from the main circuit to each of said magnets, each of which is arranged to shunt out the resistance in the main circuit and switches for closing said branch 45 circuits.
19. The combination with a main line having a plurality of substations connected in multiple thereto, of a time recording mechanism, a magnet in the main line ar- 50 ranged to control the time recording mechanism, a plurality of magnets one for each substation adapted to be connected in multiple to the main line and in series with the magnet of the time recording mechanism, 55 and a time recording mechanism embodying a plurality of recorders each controlled by one of the last mentioned magnets.
20. The combination with a line having a plurality of substations, of an electromagnet 60 connected to said line and controllable from each substation, a time recording mechanism having a recorder controlled by said magnet, a plurality of magnets one for each substation adapted to be connected in mul-
- 65 tiple to said circuit and in series with the first named magnet, and a time recording mechanism embodying a plurality of recorders each controlled by one of the last mentioned magnets.
21. The combination with a line, of a plurality of telephone instrument sets connected in multiple to said line, a time recording mechanism having a recorder controlled by any of said instrument sets, and a time recording mechanism having a plurality of 70 recorders each controlled by one of the instrument sets.
22. The combination with a line having a central station and a plurality of substations adapted to be connected in multiple 80 to the line, of an electromagnet located at central station and arranged in series with the substations, a recorder controlled by said magnet, a plurality of electromagnets adapted to be connected to the line in series with the first named magnet and in multiple with each other, each of said magnets being controlled from one of the substations, and a recorder for each of said magnets. 85
23. The combination with a line, of an 90 electromagnet arranged therein, a recording mechanism controlled by the magnet, a telephone instrument set and an electromagnet adapted to be connected in multiple to said line and in series with the first named magnet, the second named magnet being arranged to short circuit the instrument set, a recording mechanism controlled by the second named magnet, and means in proximity to the telephone instrument set for 100 breaking a circuit through the main line and effecting connection of the last mentioned magnet to the line. 95
24. The combination with a circuit, of an 105 electromagnet arranged therein, means for effecting the short circuiting of said magnet immediately after its energization, a recording mechanism controlled by said magnet, a telephone instrument set and an electromagnet adapted to be connected in multiple 110 in said line and in series with the first mentioned magnet, a recording mechanism controlled by the second mentioned magnet, a switch controlling the second mentioned magnet, a switch arranged to cut out the telephone set, and means for effecting the closing of the first mentioned switch and the opening of the second mentioned switch. 115
25. The combination with a line having 120 a central station and a substation, of an electromagnet arranged therein at the central station, means for deenergizing said magnet immediately after it has been energized, a recording mechanism controlled by said magnet, a telephone instrument set at the 125 substation, an electromagnet adapted to be connected in multiple with the telephone in-

strument set and positioned so as to short circuit said instrument set, a recording mechanism actuated by said second mentioned magnet, a switch arranged in proximity to the instrument set controlling the last mentioned magnet, a switch arranged in proximity to the instrument set for opening

the main circuit to cut out the instrument set, and means for closing one of said switches and opening the other.
